UNITED STATES PATENT OFFICE.

MAX SPUHR, OF DRESDEN, GERMANY.

BOOT-TREE.

SPECIFICATION forming part of Letters Patent No. 499,761, dated June 20, 1893.

Application filed September 28, 1892. Serial No. 447,166. (No model.)

To all whom it may concern:

Be it known that I, MAX SPUHR, a subject of the Emperor of Germany, residing at Dresden, Germany, have invented certain new and useful Improvements in Devices for Widening and Smoothing Boots and Shoes, which are illustrated in the accompanying drawings, in which—

Figure 1 is a vertical section of the device 10 taken on line $y-y$ of Fig. 3. Fig. 2 is a side view showing the iron last in section. Fig. 3 is a section taken on line $x-x$ of Fig. 1. Fig. 4 is a front view of the pressure plate and Fig. 5 is a central vertical section through the 15 guide horn.

The apparatus consists essentially of the base plate a , for sustaining the device, upon which is mounted the last section m , the other section l , being movable sidewise. In the 20 rigid half or section m , is arranged a vertical rod b , having eccentric ears c , and having also a lever e pivoted in bearings d . When the lever e is placed in a horizontal position the eccentric ears c are pressed against the movable last section l , and press the same in the 25 direction of the arrow, shown in Figs. 1 and 3. After the movable last section has been separated to the desired distance, it is locked by pressing down the lever in doing which 30 the projection f , of the lever drops into the notch g , as shown in Fig. 3. The arm h , carried by the movable section passes through the passageway i , and is provided with a coiled spring k , which upon releasing the lever e 35 presses back the movable portion of the last. The descent of the pressure plate n is attained by means of the rod o , which extends from said pressure plate to the lever p with which it is connected by means of the rack formed 40 upon the end of the rod and the teeth formed on the inner end of the lever so that the movement of the lever in the direction of the arrow shown in Fig. 2 tends to draw the plate n downward. By this means the shoe is 45 stretched at the instep in the desired manner.

In Fig. 5 is shown a work horn S in vertical section. This is adapted to be mounted on the projection t of the base plate a , and on this may be placed the model to assist the workman in the quick and accurate performance 50 of his work.

I claim—

1. In combination, the base having a vertical last section rigidly mounted thereon, a movable last section supported parallel to said 55 rigid section and mounted upon a sliding support normally under spring tension; and an eccentric journaled in the rigid part for separating the sections, substantially as described.

2. In combination with the base and rigid 60 last section, the movable section mounted upon said base, the rod b journaled in the rigid section provided with eccentrics c bearing against the movable section, and a lever e for rotating the rod, substantially as de- 65 scribed.

3. In combination with the base and rigid last section, the movable last section with means for operating the same, the vertically movable rod o , carrying the pressure plate on 70 the upper end thereof, and an operating lever mounted upon the base and connected to said rod for operating the pressure plate, substantially as described.

4. In combination the base, the rigid last 75 section, the movable last section having sliding connection with the base, the rod b journaled in the rigid section and having eccentrics bearing against the movable section, a series of notches f carried by the base, and an 80 operating lever pivoted to the rod b and having a projection f engaging the notches, substantially as described.

In witness whereof I have hereunto set my hand in presence of two witnesses.

MAX SPUHR.

Witnesses:

ALFRED H. CLARKE,
PAUL ARRAS.
